UNITED STATES PATENT OFFICE

1,973,872

HOUSING BRACKET

Thomas A. Keen, St. Louis, Mo., assignor to
Hannah M. Smith, Chicago, Ill.

Application June 12, 1931, Serial No. 543,902

10 Claims. (Cl. 272—4)

The present invention relates to an apparatus suitable for housing a car provided with a side arm and employed in dog racing, and for other purposes.

5 It is satisfactorily established that a concealed car is desirable for dog racing. Such a car carries an arm at the end of which is a lure. The greyhounds follow, their efforts being guided by sight of the lure. Their efforts are augmented by 10 the noise of the car. Greyhounds, in racing, apparently require both noise and sight of the lure to urge them to their keenest efforts.

One of the most expensive features connected with the installation of dog racing apparatus is 15 the provision of a satisfactory housing for the lure carrying car whereby the lure is conveyed about the track. The housing has always been the one to require the greatest amount of time for installation. Many structures have been suggested for housing such a car. A number of these have been used successfully, but none has been 20 altogether satisfactory.

The present invention possesses an advantage over all previous or previously proposed structures 25 in the simplicity of its construction, in the cheapness with which it may be manufactured and installed, in the quickness in which the housing may be completed, in the fact that the more expensive parts of the housing may be salvaged, an 30 impossibility with other forms of housings, and in that the present form provides the most efficient car housing so far devised.

The objects of the present invention are the provision of a new and improved means for building housing for a lure carrying car, an improved 35 car housing structure for dog racing, improved means for concealing a lure carrying car, and new and unique means for housing a lure carrying car with a minimum of construction work at a 40 race course.

These objects and such other objects as may 45 hereinafter appear, are obtained by the novel construction, unique arrangement, and improved combination of the several elements which are 50 illustrated in the accompanying drawing illustrative of a single embodiment of the invention, and in which:

Figure 1 is a transverse section of a housing and 55 a bracket therein, the subject matter of the present invention;

Figure 2 is a side elevation of a section of the housing shown in Figure 1;

Figure 3 is a horizontal section thereof.

55 Like reference characters are used to designate

similar parts in the drawing and in the description of the invention which follows.

As is conventional in other forms of housings, a trench to receive the housing is first dug. In 60 said trench, posts are set at spaced intervals, the posts being designated 10. Said posts are usually set in concrete piers 11. With its top in the same horizontal level as the top of post 10, there is disposed upon said post 10 a bracket 12 comprising an upright back portion 13 which is secured to 65 the post 11 by bolts or other fastening means, a top arm 14, and a bottom arm 15.

Upon the under surface of the upper arm 14 is 70 a transverse groove 16 in which an insulating block 17 is disposed. A similar transverse groove 18 is arranged upon the bottom arm 15. Groove 18 is generally offset from the groove 16 although this is not critical for use in housing construction.

The car 19 shown in the present apparatus has 75 offset wheels, 20 and 21, hence the tracks therefor are offset.

An insulating member 22 is arranged in the 80 groove 18 in the upper face of arm 15. In the groove 16 and spaced therefrom by the upper insulating block 17 is a conduit 23 comprising a copper rail 24 and a plug therethrough 25. In the lower channel 18 and resting on the block 22 is a brass rail 26 having a plug 27 therein. The two rails, 24 and 26, are adapted to support 85 the car 19, said car comprising side plates, 28 and 29, a motor 30, traction wheels 20 joined together by a chain 30, and an upper trolley wheel 21 which is also a guide to hold the car 19 in such position that a lure carrying arm 31 laterally disposed 90 thereon will be held in a horizontal position as the car travels about a race course. On the end of the arm 31 is a lure, not shown.

The details of the structure of the car 19 are 95 not a part of the present invention. Such a car is fully described in the patent to Thomas A. Keen No. 1,800,864, dated April 14, 1931.

The lower arm 15 of the bracket 12 has an upwardly extending section 32 having its top end 100 substantially level with the track grade at the side of the trench. In the construction of a track, posts 10 are disposed in proper foundations or piers after a trench has been dug. The brackets are then dropped into the trench and secured to the post 10 by bolts.

Boards 33 are attached to the front section 32 105 of the lower member 15 on the outer face thereof in the manner indicated, and by suitable fastening means such as bolts. The upper edge of the higher board 33, if there be more than one, is in 110

substantially the same horizontal plane of the top edge of the side section 32 of the bracket member. Board 33 is for the purpose of preventing dirt from the track reaching into the trench 5 excavated to receive the housing. The top edge of board or boards 33 is substantially in the same plane as but just above the adjacent track surface.

From the upper member 14 depends a board 34, 10 the top edge of which is in the same plane as the top arm 14 and the lower edge of which is in relatively close proximity to the top edge of the adjacent lower board 33, there being space between the two boards 33 and 34 to permit of the 15 passage of the lure carrying arm 31 without contact with either of the boards 33 and 34 in proximity thereto.

At the back of the device any suitable number 20 of boards 35 may be installed. These are attached to posts 10. After the boards 33 and 35 are attached, dirt may be filled into the trench thereagainst boards 33 on the one side and boards 35 on the other side of the housing protecting the center section of the trench in which the housing 25 is disposed from being filled in. Thus the car in the housing is fully protected from the dirt about the trench by the boards 33 and 35 just described.

Over the top of the housing, and extending 30 from the back top board 35 to the front top board 34, there may be a canvas sheet or strip 36, which is adapted to be secured in position by buttons or tacks 37 as shown. Whenever it is desired to inspect the interior of the housing, 35 the buttons 37 may be removed and the canvas 36 lifted, whereupon access to the interior of the housing may be had. If preferred, boards may be disposed upon the brackets 12 to form a top for the housing.

40 For insulating the copper and brass rails, a lug 37 may be arranged in the plugs 25 and 27 supporting the rails 24 and 26. Said lugs may extend upwardly or downwardly, as the case may be, through an aperture in the arms 14 and 15 of the bracket. Each of the arms 14 and 15 may be T-shaped or L-shaped in cross section. The aperture is through the horizontal section thereof.

45 The lugs 37 are surrounded by an insulator 38 held in position by a nut 39 which is threaded onto the said lug and which maintains said lug 37 with the aid of the insulator 38 out of engagement with any of the metallic parts of the bracket 11. Above or below each rail 24 or 26, as is proper, is a channel or longitudinal support 50 39 through which the lugs 37 extend. The channel 39 lends greater strength to the rails. Lugs 37 passing through the arms 14 and 15 first extend through the channels 39. Intermediate 55 brackets 11, there may be a number of lugs 37 extending through channel 39, the lugs in such instance being secured to channels 39 by bolts 40.

60 Thus a relatively simple mounting and reinforcement for the copper and brass conducting rails 24 and 26 is provided. The present device is adapted to be operated from a source of energy, one line of which is electrically connected to the copper rail 24 at the top and the other line to the brass rail 26 at the bottom.

65 70 The upper and trolley wheel 21 engages the copper rail 24 to act as a conductor leading to one terminal of the car motor. The other wheels 20 are electrically connected with the other terminal of said motor.

75 Complete insulation of the channel 39 and

rails 24 and 26 from the bracket 11 is obtained by the use of the channel insulating blocks 17 and 22. Each of the arms 14 and 15 has in addition to an angle iron or T-shape, an end terminating in a vertical flange to provide a suitable face for bolt holes and intended to receive the bolts which extend through the boards 33 and 34 forming the wall at the track side of the housing.

80 I claim:

1. For use in constructing a housing suitable to be used about a lure carrying car, a U-shaped member, the legs of which are substantially horizontal with one above the other, and an end member directed inwardly from the extremity of 85 the lower of said legs to provide supports for boards enclosing said housing.

2. For use in constructing a housing suitable to be used about a lure carrying car, a U-shaped member, having legs which are substantially horizontal, one of said legs being provided with a member directed inwardly in opposed spaced relation with the closed side of said U-shaped member and to provide a support for covering boards.

90 3. For use in constructing a housing for a lure carrying car, a U-shaped bracket having legs normally in horizontal planes one above the other, there being an arm projecting inwardly from the free end of the lower of said legs, and material 100 for concealing the car within said brackets secured to said legs and arm.

4. For use in constructing a housing for a lure carrying car, a unitary U-shaped bracket having a back member, legs projecting therefrom normally in a horizontal plane, and projecting arms at the free ends of said legs, said arms and legs being adapted to support material for concealing car.

105 5. In a housing, posts, U-shaped brackets disposed upon said posts, legs on said brackets normal to said posts, an arm inwardly directed from one of said legs, and covering material on said posts, legs and arm.

110 6. In a housing for a lure carrying car, posts, 120 U-shaped brackets upon said posts, rails for the lure carrying car upon the opposite legs of said bracket, arms depending from said legs, and covering for said housing secured to said posts, legs and arms.

115 7. For a car having a horizontally disposed lure support, and a housing for said car and having an opening for said support, a U-shaped bracket having legs between which said car may pass, one of said legs being below the surface of the 120 ground, an inwardly extending arm at the open end of said bracket on the lower leg thereof, the walls of said housing being secured to said legs and arms to leave an opening for the passage of the support for the lure, and said arms being 130 spaced apart sufficiently to provide for the passage of the support for the lure.

135 8. The combination with a lure carrying car having a spar for the supporting of such lure and extending horizontally from said car, of a 140 housing for said car, said housing comprising a unitary U-shaped bracket having legs between which said car passes, one of such legs being disposed horizontally below the surface of the ground, material upon said U-shaped member 145 to form the walls of said housing, the lower leg of said bracket having an inwardly extending arm, a vertical wall secured to said arm at a plane below the ground, said vertical wall extending upwardly to leave a longitudinal opening thereabove 150

higher than and parallel to the ground surface, the said opening defining the path of said spar.

9. A housing for enclosing a car and having a longitudinal opening, said car being disposed for movement longitudinally of said housing and having a horizontally disposed lure support extending through said opening for movement therein, said housing comprising a unitary U-shaped frame member arranged transversely of the walls of said housing for the support thereof, one of the opposed legs of said U-shaped member being below the ground level, inwardly extending arm means at the end of said lower leg for the attachment of a vertical housing wall thereto, said vertical wall extending upwardly to provide a lower edge for said opening, and said housing being disposed with said opening slightly above the ground level.

10. In combination, an elongated housing having walls and an opening extending longitudinally of one of said walls, a car disposed for longitudinal movement within said housing, a lure carrying spar secured to said car for movement therewith and projecting horizontally from said housing through said opening, unitary U-shaped frame members distributed at intervals along the length of said housing and transversely thereto for the support of said walls, the opposed legs of each of said U-shaped members being at the top and bottom of said housing and spaced to permit said car to pass therebetween, rails for carrying said car secured to said legs, an arm projecting upwardly from the end of each of the lower of said legs, said lower legs being disposed below the surface of the ground, and a section of the wall engaging said arms beneath the surface of the ground and extending above the surface of the ground to define the lower edge of said opening.
